US00D576029S

(12) **United States Design Patent**
Kato et al.

(10) **Patent No.:** **US D576,029 S**
(45) **Date of Patent:** **** Sep. 2, 2008**

(54) **NUT**

(75) Inventors: **Kouichi Kato**, Kanagawa-ken (JP);
Shigeo Okada, Kanagawa-ken (JP)

(73) Assignee: **Piolax, Inc.**, Yokohama-shi,
Kanagawa-ken (JP)

(**) Term: **14 Years**

(21) Appl. No.: **29/287,431**

(22) Filed: **Aug. 6, 2007**

(30) **Foreign Application Priority Data**

Feb. 8, 2007 (JP) 2007-002953

(51) **LOC (8) Cl.** **08-08**

(52) **U.S. Cl.** **D8/397**

(58) **Field of Classification Search** **D8/382, D8/387, 394, 397-399, 29; 81/121.1; 222/412; 411/81, 88, 90-93, 96-98, 103, 114, 106-108, 411/132-165, 172-189, 337, 338, 366.1-366.3, 411/368, 369, 371.2, 371.5, 418, 427, 429-432, 411/436, 437, 526, 531-538, 542, 544; D12/213**

See application file for complete search history.

(57) **CLAIM**

The ornamental design for a nut, as shown and described.

DESCRIPTION

FIG. 1 is a perspective view of the front, left side and top of a nut showing our new design;

FIG. 2 is a perspective view of the front, left side and bottom thereof;

FIG. 3 is a front view thereof;

FIG. 4 is a rear view thereof;

FIG. 5 is a top plan view thereof;

FIG. 6 is a bottom view thereof;

FIG. 7 is a left side view thereof; and,

FIG. 8 is a right side view thereof.

The elements shown in broken lines are for illustrative purposes only and form no part of the claimed design.
